UNITED STATES PATENT OFFICE

HIRAM H. HIRSCH, OF PHILADELPHIA, PENNSYLVANIA.

DESIGN FOR A BEDSTEAD.

No. 39,943.

Specification for Design.

Patented April 27, 1909.

Application filed February 23, 1909. Serial No. 479,679. Term of patent 3½ years.

To all whom it may concern:

Be it known that I, HIRAM H. HIRSCH, a citizen of the United States, residing at Philadelphia, in the county of Philadelphia and State of Pennsylvania, have invented a new, original, and ornamental Design for Bedsteads, of which the following is a specification, reference being had to the accompanying drawing, forming part thereof.

The figure is a perspective view showing my new design.

I claim:

The ornamental design for a bedstead, as shown.

HIRAM H. HIRSCH.
